VIOLIN REST

Rudolph H. Heimers, Coronado, Calif.

Application July 25, 1949, Serial No. 106,563

3 Claims. (Cl. 84—281)

1

My invention relates to a violin rest, more particularly for use in aiding the violinist in maintaining his violin in certain playing position, and the objects of my invention are:

First, to provide a violin rest of this class which fixes the transverse angle of inclination of a violin in conformance to the natural playing attitude of a violinist, whereby uniformity of position may be maintained at all times, either during the playing of violin in sitting or standing position;

Second, to provide a violin rest of this class which engages the scroll of a violin at the end thereof, and maintains the proper angle of inclination of the violin, so that the proper relaxed position of the fingers of the violinist upon the finger board and the respective arm of the violinist, is promoted;

Third, to provide a violin rest of this class having very simple and positive means for adjusting the angle of inclination of a violin when in playing position, whereby different attitudes of different violinists may be accommodated;

Fourth, to provide a violin rest of this class having novel adjusting clutch means for maintaining certain fixed positions of the violin rest with respect to the desired angle of inclination of the instrument to be played in engagement with said rest;

Fifth, to provide a violin rest of this class which is particularly adapted for use in training student violinists in the proper position for playing with respect to a certain angle of inclination of the instrument;

Sixth, to provide a violin rest of this class which is very readily and easily adjusted vertically to accommodate violinists in either sitting or standing position; and

Seventh, to provide a violin rest of this class which is very simple and economical of construction, efficient in operation, and which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters of reference thereon, forming a part of this application, in which:

Fig. 1 is a fragmentary perspective view of my violin rest, showing a violin engaging the same and the relative position of a violinist playing the violin; Fig. 2 is a perspective view, similar to Fig. 1, showing the complete structure of my

violin rest, and illustrating by dash lines the hanging position of the violin and the bow when not in use; Fig. 3 is a top or plan view of my violin rest; Fig. 4 is an enlarged fragmentary sectional view, taken from the line 4—4 of Fig. 3; Fig. 5 is an enlarged fragmentary sectional view, taken from the line 5—5 of Fig. 4; and Fig. 6 is an enlarged fragmentary sectional view, taken from the line 6—6 of Fig. 2.

Similar characters of reference refer to similar parts and portions throughout the several views of the drawing.

The base 1, pedestal 2, post 3, clamp bolt 4, bow hanger 5, casing 6, scroll-engaging socket member 7, clutch plate 8, clutch face plates 9 and 10, bolt 11, head bearing 12, pin 13, clutch arm 14, upholstery 15, hinge 16, latch 17, and the instrument hanger 18, constitute the principal parts and portions of my violin rest.

The base 1 is a flat plate-like member, having a foot rest upper surface portion 1a, on which the violinist's foot may be placed when in standing position, and this base 1 is also provided with a chair leg receiving recess 1b, which is adapted to receive the left front leg of a chair in which the violinist sits when playing in sitting position. Fixed to the base 1 is the hinge 16, which connects the pedestal 2 in pivotal relationship with the base 1. The pedestal is provided with an upright post 2, having laterally extending leg portions 2a, and 2b. The hinge 16 is fixed to the leg portion 2b, near the bottom of the pedestal 2, and the latch 17, which is a conventional cupboard latch, or the like, engages the leg 2a of the pedestal 2 for fastening the same in connection with the base 1, against pivotal movement of the pedestal 2 about the axis of the hinge 16.

Extending from the pedestal 2 considerably above the base 1, on which it rests, is the clamp bolt 4. This clamp bolt 4 is provided with a wing nut 4a, on its extending externally screw-threaded end, which is adapted to clamp the post 3 in certain elevated position on the pedestal 2. This post 3 is provided with a vertically disposed longitudinal slot 3a, through which said clamp bolt 4 extends, all as shown best in Figs. 2 and 6 of the drawings. Secured to the post 3 by means of the wing nut 4a is the bow hanger 5, on which the violin bow may be supported when not in use. Secured to the clamp bolt 4 is the instrument hanger 18, as shown in Fig. 2 of the drawings, which is a simple loop of flexible material, through which the scroll of a violin may be positioned, as shown by dash lines in Fig. 2 of the drawings.

Fixed to the upper end of the post 3 is the cas-

ing 6, which casing 6 is provided with a cylindrical portion 6a, and a back plate 6b, all in rigid fixed relationship with the post 3. Revolvably mounted in the cylindrical portion 6a is the scroll-engaging socket member 7. This scroll-engaging socket member 7 is provided with an obtuse conical recess portion 7a, having a substantially rectangular recess portion transversely thereof, which is designated 7b, and which extends to a greater depth than the obtuse apex of the conical recess 7a, all as shown best in Fig. 4 of the drawings. Positioned at the bottom of the transverse recess 7b is the head bearing 12, which engages the head of the bolt 11, which is revolvably fixed in the back plate 6b of the casing 6 by means of the pin 13 in the slot 6c. The bolt 11 is longitudinally adjustable by means of the nut 11a, externally screw-threaded thereon, providing for the compression of the scroll-engaging socket member 7 against the clutch plate 8, and the face plates 9 and 10, at opposite sides thereof.

As shown in Fig. 4, it will be seen that the clutch plate 10 is of smaller diameter and reduced area compared to the clutch face plate 9, and this face plate 10 engages the member 6b of the casing 6, while the clutch face plate 9 is interposed between the clutch plate 8 and the scroll-engaging socket member 7. Fixed to the clutch plate 8 is the clutch arm 14, which is movably mounted in a slot 6d in the casing 6, all as shown best in Fig. 4 of the drawings. The normally lower end of the clutch arm 14 is provided with a loop portion 14a, which engages the slot 3a of the post 3, for maintaining the scroll-engaging socket member 7 in certain fixed relationship to the vertical or horizontal, as desired, whereby the recess 7b is disposed at a certain inclination angle, as desired by the violinist for the maintenance of his instrument in proper playing position, according to his requirements.

The outer face of the scroll-engaging socket member 7 is provided with soft upholstering 15, having inwardly disposed skirt portions 15a, compressively secured on the outer sides of the scroll-engaging socket member 7 by means of rubber bands 15b, which force the upholstery skirt 15a into an annular groove portion 7c peripherally of the scroll-engaging socket member 7.

The operation of my violin rest is substantially as follows: It is to be here noted that the casing 6, together with the scroll-engaging socket member 7, clutch plate 8, clutch facings 9 and 10, bolt 11, and cooperative parts, may be fixed to a wall or the like, without using the post 3, pedestal 2, or other supporting means, if desired. When a violinist is desirous of employing my violin rest, as shown in Fig. 2 of the drawings, he rests a foot on the foot engaging surface 1a of the base 1, and places the scroll of his violin in the conical recess 7a of the scroll-engaging socket member 7, whereupon bearing of the scroll is accomplished normal to the inwardly extending recess 7b, which bears transversely of the arc or curve at the end of the violin scroll. In order to adjust the scroll-engaging socket member 7 revolvably of the axis of the bolt 11, to accommodate the particular angle of inclination desired by the violinist, the nut 11a on the bolt 11 may be loosened, and the clutch face plate 9 may be slidably adjusted revolvably until the recess 7b is at the desired angle relative to the horizontal. The nut 11a then may be tightened, forcing frictional engagement of the clutch face plates 9 and 10 with the clutch plate 8 and the scroll-engaging socket member 7.

The revoluble adjustment of the scroll-engaging socket member 7 about the axis of the bolt 11 may then be accomplished by shifting the clutch arm 14, whereupon the clutch face plate 10 slides, while the clutch face plate 9 maintains fixed relationship of the scroll-engaging socket member 7 relative to the clutch plate 8, causing the scroll-engaging socket member 7 to concisely follow the rotary motion of the clutch plate 8, controlled by the clutch arm 14. This clutch arm 14 is resilient, and the loop 14a thereof may be disengaged from the slot 3a in the post 3 by deflecting the same outwardly. When it is desired to employ my violin rest by violinists in the sitting position, the chair of the violinist rests with one leg thereof in the recess 1b of the base 1, lending stability to the pedestal 2 which supports the scroll-engaging socket member 7. When it is desired to collapse my violin rest, the latch 17 is released, permitting the pedestal 2 to be hinged into adjacent relationship with the upper surface 1a of the base 1, which renders said violin rest substantially portable.

It will be noted that weight may be added to the pedestal 2 at its lower end, which would eliminate the necessity of bearing on the base 1 with either the foot or a chair-leg. Thus, the base might be eliminated or reduced in size.

When playing in the standing position, a violinist may leave the left front leg of the chair in the recess 1b of the base 1, and pivotally shift the same toward the pedestal 2, so that the player need not hold the base 1 with his foot.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. A violin rest consisting of a scroll-engaging socket member having a recessed socket portion provided with opposed side walls engageable with opposite sides of a violin scroll at its extremity, means for supporting the same, said scroll-engaging socket member pivotally adjustable on a horizontal axis substantially parallel to the longitudinal axis of a violin when engaging said socket member, a clutch intermediate said scroll-engaging socket member and said means, and an arm in connection with said clutch for pivotally shifting said scroll-engaging socket member.

2. A violin rest consisting of a scroll-engaging socket member having a recessed socket portion provided with opposed side walls engageable with opposite sides of a violin scroll at its extremity, means for supporting the same, including a horizontally disposed bolt substantially parallel to the longitudinal axis of a violin when engaging said socket member, on which said scroll-engaging socket member is pivotally mounted, a clutch for fixing said scroll-engaging socket member relative to said means for supporting the same, said clutch including a clutch plate, having a clutch facing thereon adjacent said scroll-engaging socket member, and a second clutch facing on the opposite side thereof of lesser area than the first-mentioned clutch plate, engageable with said means for supporting said scroll-engaging socket member, whereby said second clutch facing is movable during seizure of said first clutch

facing with said clutch plate and said scroll-engaging socket member.

3. In a violin rest consisting of a scroll-engaging socket member having a recessed socket portion provided with opposed side walls engageable with opposite sides of a violin scroll at its extremity, means for supporting the same, said scroll-engaging socket member pivotally mounted on said means on a horizontal axis substantially parallel to the longitudinal axis of a violin when 10 engaging said socket member, said scroll-engaging socket member having a conical recess portion therein, said conical recess portion being obtuse and having a secondary central rectangular recess extending beyond the apex of said obtuse 15 conical recess.

RUDOLPH H. HEIMERS.
